UNITED STATES PATENT OFFICE.

ALBERT O. PRICE, OF COSHOCOTON, OHIO, ASSIGNOR TO JERRY A. COMPTON, OF COSHOCOTON, OHIO.

PHONOGRAPH RESONANCE BOX.

1,407,574.

Specification of Letters Patent. Patented Feb. 21, 1922.

Application filed October 9, 1919. Serial No. 329,487.

To all whom it may concern:

Be it known that I, ALBERT O. PRICE, a citizen of the United States, residing at Coshocton, in the county of Coshocton and State of Ohio, have invented certain new and useful Improvements in Phonograph Resonance Boxes, of which the following is a specification.

This invention relates to an improvement 10 in tone chambers for phonographs and has as its object to provide a tone chamber which will, to a greater degree than the ordinary tone chamber now in use, enhance the quality of the tones and respond equally well to all 15 tones.

The invention contemplates the provision of a tone chamber having a resonant area of such size that some portion or another of it will respond to the highest or to the lowest 20 tone so that various tones will be equally and impartially improved in depth and quality and in this respect the tone chamber of the present invention differs materially from a tone chamber having only a rectangular effective area which is limited in its responsiveness to the various tones due to its peculiar size and outline.

In the accompanying drawings:

Figure 1 is a perspective view of a cabinet phonograph equipped with the tone chamber embodying the present invention;

Fig. 2 is a horizontal sectional view through the tone chamber on the line 2—2 of Fig. 3;

Fig. 3 is a vertical longitudinal sectional view therethrough on the line 3—3 of Fig. 2.

The base of the tone chamber embodying the invention comprises a sounding board, indicated by the numeral 1, this board being 40 relatively thin and of any of the various woods or metals employed in the manufacture of musical sounding boards. At its margin the board 1 is supported upon a base frame, indicated in general by the numeral

45 2, this frame being, as also the board, rectangular in outline and being designed for location within the body of the phonograph cabinet in the manner shown in Fig. 1 of the drawings. This cabinet is indicated in general

50 in the drawings by the numeral 3 and is provided with the usual open front 4 through which the sound waves issue. The top or base upon which the sound arm is mounted for turning movement is indicated in general by the numeral 5 and the said sound

arm is indicated at 6. The throat of the tone chamber includes a rear wall 7, side walls 8 and a front wall 9, the throat being here shown as rectangular, although it may assume some other configuration if found desirable. In any event it is mounted at its lower end upon the sounding board 1 at the rear side thereof and if desired a block 10 may be placed in the lower end of the throat and provided with a deflecting surface 11 for directing the sound waves in a general forward direction and through the forward side of the said throat which is open, as at 12, at its lower portion.

The tone chamber proper includes side 70 walls 13 and a top wall 14, the side walls 13 are connected at their rear ends to the opposite sides of the open front 12 of the throat of the box and extend forwardly in diverging planes and preferably terminate at their 75 forward ends at the forward corners of the base. The lower edges of the side walls 13 of the box rest square upon the upper surface of the sounding board 1 and are secured firmly in this position by screws or other 80 fastening elements 15. The upper edges of the side walls 13 of the tone chamber are inclined upwardly and forwardly from the rear ends of the said side walls and the top wall 14 is disposed at its lateral edges upon 85 the said upper edges of the side walls and secured thereto in any suitable manner. The top 14 is therefore inclined upwardly and forwardly and it is gradually increased in width in the direction of its forward end. 90 It will now be understood that the tone chamber is, generally speaking, flared from its throat end to its mouth end and that the bottom wall of the box is resonant, being in the nature of a sounding board. It will also 95 be apparent that the surface width of that portion of the area of the sounding board 1 which lies between the side walls 13 of the tone chamber varies throughout the length of the box, or in other words, gradually increases from the throat end of the box to the mouth end thereof. Due to this fact some portion or another of this part of the surface of the sounding board, which part of the surface constitutes the most effective area 100 of the board, will respond to any tone whether it be high, low or medium. For example, the narrower portion of the effective sounding board will vibrate most in response to the higher tones and the broader portions 105 110

of the effective board will vibrate most in response to the lower tones.

While that part of the sounding board lying between the side walls of the tone chamber has been termed the effective area of the said board, nevertheless, it will be understood that the parts of the board exterior to the tone chamber proper will also be more or less effective in improving the quality of the tones.

Having thus described the invention, what is claimed as new is:

1. In sound reproduction apparatus, a cabinet having a compartment, a relatively thin horizontally disposed sounding board forming the bottom of said compartment, and a tone chamber housed within the compartment and comprising a throat having its delivery end located at the upper side of the said sounding board, side walls secured to and upstanding from the sounding board and arranged in planes diverging in a forward direction from the said delivery end of the throat, and a top wall extending between the side walls and inclined upwardly and forwardly from the said end of the throat.

2. In sound reproduction apparatus, a tone chamber comprising a relatively thin sounding board forming the bottom of said chamber, a sound delivery throat having its delivery end located at the upper side of the said sounding board, side walls secured to and upstanding from the sounding board and arranged in planes diverging in a forward direction from the delivery end of the

throat, and a top wall extending between the side walls and inclined upwardly and forwardly from the said end of the throat, the sounding board at opposite sides projecting beyond the planes of the said side walls and having its projecting portions free from contacting parts.

3. In sound reproduction apparatus, a cabinet, a relatively thin, resonant sounding board extending from front to rear and from side to side completely across the interior of the cabinet, one wall of the cabinet having a sound delivery opening having its lower side located substantially in the plane of the sounding board, a delivery throat having its delivery end located immediately above the sounding board and substantially midway of the opposite wall of the cabinet and side and top walls constituting in conjunction with the sounding board a tone chamber, the said side walls extending from the delivery throat to the delivery opening in forwardly diverging planes and having their lower edges disposed continuously in contact with the upper surface of the sounding board, the top wall of the tone chamber extending between the upper edges of the side walls and being inclined upwardly from the delivery throat to the delivery opening, the side walls and top wall terminating at their forward ends respectively at the sides and top of the delivery opening, the sounding board, beyond the sides of the tone chamber, being devoid of contacting parts.

In testimony whereof I affix my signature.

ALBERT O. PRICE. [L. S.]
